UNITED STATES PATENT OFFICE.

FRANCIS X. LENGS, OF CLEVELAND, OHIO.

CRUTCH.

Application filed June 11, 1923. Serial No. 644,635.

To all whom it may concern:

Be it known that I, FRANCIS X. LENGS, a citizen of the United States, residing at Cleveland, in the county of Cuyahoga and 5 State of Ohio, have invented a certain new and useful Improvement in a Crutch, of which the following is a full, clear, and exact description, reference being had to the accompanying drawings.

10 This invention relates to crutches and more particularly to that type of crutch having a yieldable arm piece or saddle.

One of the objects of this invention is the provision of an attachment which may be 15 readily secured to the arm piece without necessitating the removal of the arm piece from the staff. In this connection, my invention contemplates the provision of an attachment which is quite simple in construction, and which permits vertical movement 20 relatively to the staff and at the same time enables the shoulder of the user to rock and tilt on the yieldable support, so as to give a maximum degree of comfort.

25 The means for carrying out my invention will hereinafter be fully set forth in the following description which pertains to the accompanying drawings. The essential features of my invention will be summarized 30 in the claims.

In the drawings, Fig. 1 is an elevation of a 35 crutch having my invention attached thereto; Fig. 2 is a vertical section taken through a portion of the crutch adjacent the upper end thereof; Fig. 3 is a plan view of my invention with the padded shoulder piece removed, and Fig. 4 is a sectional view on an enlarged scale similar to that shown in Fig. 2.

40 In the crutch shown in the drawings, the standard comprises a lower part or staff and a bifurcated upper portion 11, between which at the proper elevation is disposed the usual hand grip 12. Adjacent the top of 45 the upright is an arm piece or saddle 13 which in the usual embodiment has a curved upper surface 14, which is engaged by the arm pit or shoulder of the user.

My invention, as heretofore stated, 50 comprises an attachment which may be connected to the arm piece and which may provide a yieldable support or rest for the user. In the preferred embodiment, the attachment 55 comprises a bridge member which is rigidly connected to the arm piece, and is adapted to position the yieldable means.

The bridge member preferably comprises a stamping, having integral sides 16 and connecting portions 17. Each of the connecting portions have the outer ends in engagement with the surface 14 of the arm piece, and have inwardly extending arms 17, the inner ends of which are spaced from each other and are each provided with a slot 18, as shown in Fig. 3. These arms are 60 independently movable and serve to position the spring and to support a shoulder pad. 65

The yielding support is attained by the use of a spring 20, which comprises a leaf spring having the ends, as at 21, curved upwardly to provide a sliding engagement 70 with the surface 14 of the arm piece, and having the intermediate portion, as at 22, curved oppositely to the end portions, whereby the spring may be passed through the slots 18 and positioned by the arms 17. A pad 25 may be disposed above the bridge member and firmly attached thereto. 75

When the user's weight is directed vertically upon the pad, the ends of the spring 80 slide equally and outwardly. When the weight of the user is directed either forwardly or backwardly, however, then one end of the spring is moved a greater distance than the opposite end, and one of the 85 arms 17 is depressed to a greater extent than the opposing arm. Thus the attachment provides a resilient support which counteracts vertical stresses as well as lateral stresses placed upon the arm piece by the user. 90 An advantage of a device constructed in accordance with my invention is the adaptability for attachment to existing crutches, and the comfort afforded to the user. 95

Having thus described my invention, I 100 claim:—

1. In a device of the character described, the combination with the arm piece of a crutch, of a member rigidly connected with the arm piece and having a portion thereof projecting inwardly toward the center of the arm piece and a spring carried by said portion, said spring having the ends thereof adjacent the arm piece. 105

2. In a device of the class described, the combination with an arm piece of a crutch, of a pair of opposed arms, carried thereby, each having the outer ends thereof carried by said arm piece, and having the inner ends thereof spaced from each other, and a spring operatively connected to the inner ends of said arms. 110

3. In a device of the character described, the combination with the arm piece of a crutch, of a member rigidly attached to the crutch, and having a yieldable portion extending toward the center of the arm piece, and a spring carried by the yieldable portion and slidably engaging the arm piece.
4. In a device of the character described, the combination with an arm piece of a crutch having a concave upper surface, of a bridge member carried by the arm piece and having a pair of inwardly extending arms projecting across the concave portion of the arm piece, a spring operatively connected to both of said inwardly extending arms, and engaging the upper surface of said arm piece.
5. In a device of the class described, the combination with the arm piece of a crutch, of independently movable members, each having one end thereof attached to the arm piece, and a spring carried by the free ends of said members, said spring slidably engaging said arm piece.
6. In a device of the class described, the combination with the arm piece of a crutch, of a member rigidly attached to said arm piece, a spring carried intermediately by said member and having the ends thereof slidably engaging said arm piece.
7. In a device of the class described, the combination with a bowed arm piece, of a member rigidly attached to said arm piece,
8. In a device of the class described, the combination with the arm piece of a crutch of a bridge member having a portion thereof engaging the side of said arm piece, and having other portions engaging the top of the arm piece, extension pieces projecting inwardly from the top engaging portion and having the opposed ends thereof spaced from each other, a spring operatively connected to said extension pieces and slidably engaging said arm piece.
9. In a device of the class described, the combination with the arm piece of a crutch, of a bridge member having portions thereof engaging the sides of the arm piece, and having intermediate portions engaging the top of the arm piece, a pair of inwardly extending arms integral with the bridge member, said arms having the opposed ends thereof spaced from each other, and each having a slot therein, a leaf spring having the ends thereof slidably engaging the arm piece, and having the intermediate portion extending through said slots, and a pad carried by said arms.

In testimony whereof I hereunto affix my signature.

FRANCIS X. LENGS.
